WEIGHTING MEANS FOR SPINNING FRAMES

Charles Morton, Pawtucket, R. I.

Application March 24, 1932, Serial No. 600,869

14 Claims. (Cl. 19—135)

This invention relates to a spinning machine, and has for one of its objects to tension or weight the nip rolls between which the yarn is passed for drafting, the same being an improvement on my co-pending applications Serial Nos. 531,868, filed April 22, 1932 and 571,517, filed October 28, 1931.

Another object of the invention is the provision of weighting means which will permit of the 10 nip rolls running relatively close together that long draft spinning may be had.

Another object of this invention is to provide 15 weights so arranged that the back and front rolls of the frame may be independently weighted or tensioned.

Another object of the invention is the provision 20 of weighting means for both the back and front rolls located generally in the same plane but which are arranged so as not to interfere one 20 with the other.

Another object of this invention is the provision 25 of weighting means such that the front rolls of the back to back units may be commonly weighted and the back rolls of each unit independently weighted, all substantially in the same plane.

A further object of this invention is the provision 30 of weighting means which will permit of ready access to the intermediate roll between the weighted or nip rolls for removal of the top intermediate roll when desired without disturbing 35 the weighting means.

A still further object of the invention is the provision 35 of a construction by which the weights may act through levers which will be positioned so as to be out of the way and will not unduly obstruct the manipulation of the machine.

With these and other objects in view, the invention consists of certain novel features of construction, as will be more fully described, and 40 particularly pointed out in the appended claims.

In the accompanying drawings:

Fig. 1 is a sectional view through the spinning machine showing two roller stands back to back with the weighting means below the breast beam 45 of the machine.

Fig. 2 is a section on line 2—2 of Fig. 1.

Fig. 3 is a section on line 3—3 of Fig. 1 showing two different weights with the back roll not shown and the weight and leverage mechanism 50 for the back roll omitted in the left hand showing of the weight for the sake of clearness.

Fig. 4 is a view of one weighting means in a view similar to Fig. 3 showing a modified form of weighting, the common weight between two 55 units being round and the separate weight for

the back roll disposed to partially receive the same.

Fig. 5 is a perspective view of the weights shown in Fig. 4.

Fig. 6 is a sectional view of one of the units 5 shown in Fig. 1 with a modified form of weight for the back roll, the weight being multiplied through a leverage connection and being entirely above the breast beam.

Fig. 7 is a perspective view of the lever and 10 weight shown in Fig. 6.

Fig. 8 is a sectional view similar to Fig. 1 showing the two units with common weights for both the back and front rolls directly connected to these rolls in each of the units.

Fig. 9 is a section on line 9—9 of Fig. 8.

In spinning machines the nip rolls, which grip the yarn under sufficient pressure to prevent slipping and thus causing a drafting or pulling out of the fibers, are either themselves sufficiently 20 large to apply the weight desired, are weighted by additional rolls in contact with the top roll or are weighted by the direct application of weights, which, in some instances may be multiplied by levers in their action on the top rolls. 25 This invention deals more particularly with the latter type.

In prior machines where the nip rolls are sufficiently large to apply their own weight, the nip rolls cannot be placed sufficiently close together for long draft because of this large diameter of the rolls themselves. This objection is also, to some extent, present where additional weight rolls engage the upper roll of the pair of nip rolls and in other cases obstruct removal 35 of the intermediate carrier rolls.

In the placing of the rolls close together for long draft spinning, some attention must be given to the drive of these rolls, and I have provided for this as described in my prior Patent Nos. 40 1,619,985 dated March 8, 1927, 1,619,986 dated March 8, 1927 and 1,783,301 dated Dec. 2, 1930. My weighting means in this present invention is such that it will not interfere with the close setting or the drive of the rolls as I have applied 45 the weights at the back and front of the nip rolls with none of the parts extending between the points of nip of the rolls so that no such interference will result. I have also found that with certain traverse motions, that too bulky an arrangement of weights will interfere with this 50 traverse motion, and I have therefore made a very compact arrangement of weights in this present invention, so that the weighting means will have their centers in a common vertical 55

plane passing through the points of attachment of these weights to the back and front rolls; and I have arranged the weights in some instances one within the other that this object may be more fully and completely carried out; and the following is a detailed description of the present embodiment of this invention illustrating the preferred means by which these advantageous results may be accomplished.

- 5 10 With reference to the drawings, 10 designates the breast beam of the machine on which there is supported two back to back spinning units each shown here as supported by a standard 11 having a pedestal 12 resting on the breast beam.
- 15 15 Each of these units supports a group of rolls comprising aligned front rolls 13 and 14, back rolls 15 and 16 and intermediate rolls 17 and 18, all rotatably supported in the customary manner, the three line unit being shown, although this 20 invention may be similarly applied to the four line roll system if desired.

The upper rolls 14 of each unit are weighted by a common weight 19 generally rectangular in cross-section provided with a series of openings 25 at each of its ends into which the links 21 may be hooked, the latter being hinged to the curved links 22 which are hooked at their upper end to engage the reduced portions 23 between the working surfaces 24a of the rolls to apply 30 weight thereto.

Openings or slots 24 are provided in the common weight 19, in which openings there are suspended individual weights 25 for applying pressure to the top back roll 16 of each unit through 35 the suspension member 26 connected to lever 27 which in turn is connected by link 28 to the lever 29, fulcrumed as at 30 and bearing upon the reduced portion 31 between the working surfaces 32 of the back roll, and by this arrangement I may multiply the pressure applied to the 40 back roll in any desired relation such as for instance as herein shown as four to one, by which arranged I may use a small weight and have a correspondingly small opening in the weight 45 19 in which the same is suspended whereby the mass or bulk of the weight 19 may be maintained at a minimum.

In Fig. 4 I have illustrated the common weighting means for the front roll as consisting of a weight 33 generally cylindrical in shape or circular in cross-section, the same being reduced as at 34 to provide a fin 35 with openings 36 therein for receiving the hook on the link 21 in the usual manner. Instead of cutting out a portion of this weight 33 to receive a weight within it as described above, I have provided an arc shaped weight 37 which itself partially receives the common weight 33 extending between the units for weighting the front rolls thereof. In 55 this manner the weights are kept compact and the points of connection and pull and the center of the nip rolls are all maintained in substantially the same vertical plane.

Fig. 6 illustrates the common weight 33 for both 60 units which may be of any desired cross-section shape, and instead of providing a weight below the breast beam 10 I have mounted the weight 39 directly on the lever arm 27 thus positioning this weight 39 above the breast beam 10, this weight being adjustable along the arm and held in position by a suitable set screw 40.

In each of these constructions above described which embody the lever 27 the same is pivoted about a fulcrum 41 consisting of an inverted U shaped member 42 adjustably mounted in the

breast beam 10 by means of the threaded portion 43 and nut 44, whereby the desired height of the weighted end of the lever 27 may be maintained with reference to the breast beam 10.

In some instances it is desirable to apply the weight directly to the back roll and to commonly weight the back rolls of two back to back units of a spinning frame. In Fig. 8 I have illustrated an arc shaped weight 45 as hanging over and partly receiving the weight 33 as described in connection with Figs. 4 and 5 and extending a substantial length therealong, the same being provided with points of attachment 46 adjacent each end which are connected by links 47 and 48 directly to the reduced portion of the back roll 15 between the working surfaces thereof. The openings 49 through the breast beam permit the passage of these links and the unobstructed application of this pressure along the links to the back rolls.

By this arrangement I am enabled to connect the weights so that their center of mass or pull is in the plane with the point of connection of the weights to the rolls, thereby applying a pull or pressure upon the rolls in the desired direction without twist or distortion or requirement of balance. Also by this arrangement I provide a minimum number of parts which is important where disconnection is desired for removal of any of the rolls. The construction is such that the 30 weights may act independently on the back and front rolls without interference with each other and yet close positioning of the rolls is permitted that long draft spinning may be had. Further, the weights are so arranged that the intermediate rolls may be lifted from position as desired without removing or disturbing any of the weights used, and the weights are housed one within the other that the minimum bulk or space is occupied.

The foregoing description is directed solely towards the construction illustrated, but I desire it to be understood that I reserve the privilege of resorting to all the mechanical changes to which the device is susceptible, the invention 45 being defined and limited only by the terms of the appended claims.

I claim:

1. In a spinning machine, a support, a pair of spinning units positioned back to back on said support, each having pairs of draft rolls, a common weight extending between said units and below said support for applying pressure to one of the pairs of rolls of each unit, and additional weighting means for one of the other pairs of draft rolls located horizontally below said support and having its center of mass in a plane passing vertically through the center of mass of said common weight.

2. In a spinning machine, a pair of spinning units positioned back to back, each having pairs of draft rolls, a common weight extending between said units for applying pressure to one of the pairs of rolls of each unit, and an additional weight common to one of the other pairs of draft rolls of each unit and having its center of mass located within the common weight.

3. In a spinning machine, a support, a plural- 60 ity of pairs of draft rolls above said support having points of attachment for weighting means 65 all located in a common vertical plane, and independent weighting means below said support for said pairs of rolls having their centers of mass located one within the other and in substantially the vertical plane of said points of at- 75

tachment but out of the same horizontal plane, the horizontal axis of each of said weighting means extending in the same direction.

4. In a spinning machine, pairs of draft rolls

5 having points of attachment for weighting means located in a common vertical plane, and independent weighting means for said pairs of rolls having their centers of mass located one within the other and in substantially the vertical plane 10 of said points of attachment but out of the same horizontal plane.

5. In a spinning machine, pairs of draft rolls having points of attachment for weighting means located in a common vertical plane, and inde-

15 pendent weighting means for one of said pairs of rolls, additional weighting means for another pair of rolls, said weighting means having their centers of mass located one within the other and in substantially the vertical plane of said points 20 of attachment, the center of mass of said additional weighting means being located in substantially a common horizontal plane with that of said first weighting means.

6. In a spinning machine, pairs of draft rolls 25 for nipping the yarn, separate weights for each of said pairs of draft rolls, the arrangement of said weights being such that one weight is located within the other.

7. In a spinning machine, pairs of draft rolls 30 for nipping the yarn, having points of attachment for the weighting means located in a common vertical plane, separate weights for said pairs of draft rolls also located in said common vertical plane, the arrangement of said weights 35 being such that one weight is located within the other, the centers of said weights being located in said plane.

8. In a spinning machine, pairs of draft rolls 40 for nipping the yarn, separate weights for said pairs of draft rolls, one of said weights having an opening therein and the other weight extending through said opening.

9. In a spinning machine, pairs of weighting 45 means, pairs of draft rolls having points of attachment for the weighting means located in a common vertical plane at right angles to the axis of said rolls, one of said weighting means having an opening therein and secured to one of said points of attachment and the other weighting

means suspended from another point of attachment and extending through said opening.

10. In a spinning machine, a pair of spinning units positioned back to back, each having pairs of draft rolls, separate weights one within the other, both weights extending from one unit to the other, one weight being common to one pair of rolls in each unit and the other weight being common to the other pair of rolls in each unit. 5

11. In a spinning machine, a pair of spinning 10 units positioned back to back, each having pairs of draft rolls, separate weights, one weight being common to one pair of rolls in each unit and extending from one unit to the other and having an opening therein and another weight with- 15 in said opening.

12. In a spinning machine, a pair of spinning units positioned back to back, each having pairs of draft rolls with points of attachment for weights and located in a common vertical plane, 20 separate weights for said pairs of rolls, one being common to one pair of rolls in each unit and the other being common to the other pair of rolls in each unit, one of said weights having an opening therein and the other weight being located in said opening. 25

13. In a spinning machine having a breast beam, a pair of spinning units positioned back to back, each having pairs of draft rolls, a common weight below the breast beam, means to connect it to apply pressure to the front rolls of each unit, and individual means above the breast beam to apply pressure to the back pair of rolls of each unit, said means consisting of separate levers each pivoted on the breast beam and having a weight slideable thereon and a link connecting each lever to the back pair of rolls of each unit. 30 35

14. In a spinning machine, a pair of spinning units positioned back to back, each having a plurality of pairs of draft rolls intersecting a vertical plane, a common weight extending between said units for applying pressure to one of the pairs of rolls of each unit, and additional weighting means for another of the pairs of rolls of each unit, the center of mass of said additional weighting means being in a vertical plane passing through the said common weight. 40 45

CHARLES MORTON.
